UNITED STATES PATENT OFFICE.

JOHN H. BROMLEY, OF PHILADELPHIA, PENNSYLVANIA, ASSIGNOR TO JOHN BROMLEY & SONS, OF SAME PLACE.

DESIGN FOR CARPET.

Specification forming part of Design No. 7,565, dated July 21, 1874; application filed July 11, 1874.
[Term of Patent 3½ years.]

To all whom it may concern:

Be it known that I, JOHN H. BROMLEY, of Philadelphia, Pennsylvania, have invented a new and Improved Design for Carpets; and I do hereby declare that the accompanying photographic illustration is a correct representation of my invention, fully setting forth the nature of it.

What I claim as new, and desire to secure by Letters Patent, is—
The design for carpets, as shown.

JOHN H. BROMLEY.
